UNITED STATES PATENT OFFICE.

CHARLES WINTHROP CARMAN, OF HEMPSTEAD, NEW YORK.

THREAD-CUTTING ATTACHMENT.

1,173,769.

Specification of Letters Patent. Patented Feb. 29, 1916.

Application filed July 2, 1915. Serial No. 37,678.

To all whom it may concern:

Be it known that I, CHARLES W. CARMAN, a citizen of the United States, and a resident of Hempstead, in the county of Nassau 5 and State of New York, have invented a new and Improved Thread-Cutting Attachment, of which the following is a full, clear, and exact description.

Among the principal objects which the 10 present invention has in view are: to provide a thread-cutting attachment for a sewing machine, arranged adjacent the path of travel of the material being sewed, so that the operator may cause the same to be severed by a slight turn of the thread connecting a series of articles; to provide means for 15 mechanically severing a continuous thread uniting the articles manufactured in chain form; and to provide a simple, and efficient 20 thread-cutting mechanism for employment in types of sewing machines known as factory machines.

Drawings.—Figure 1 is a plan view of a 25 sewing machine head, having applied thereto a thread-cutting attachment, constructed and arranged in accordance with the present invention; Fig. 2 is a perspective view of the same; Fig. 3 is a detail view on an enlarged scale, showing in vertical elevation, 30 a thread-cutting attachment of the character mentioned, the cover of the knife guard being removed; Fig. 4 is a cross section of the rotary knife and mounting therefor, the section being taken as on the line 4—4 in Fig. 1; Fig. 5 is a face view of the detachable cover for the knife guard; and Fig. 6 is a view, showing a series or chain of articles 35 united by the thread with which they are sewed, constructed in the manner usual 40 in the manufacture of such articles at the present time.

Description.—In Fig. 6 of the accompanying drawings, a series of salt bags, is shown, the adjacent members being connected with 45 a short length of thread, which short lengths of thread are portions of the thread employed in constructing the bags. The practice has been to run off a chain of articles, such as the bags 11, the connecting thread 50 12 being subsequently severed by hand. This method has necessitated the employment of extra help to perform this service. A further objection has arisen, in that the connection formed by the thread 12 has interfered with the packing of the bags, compelling an arrangement of the bags in piles, 55 whereby the individual bag is reversely disposed in relation to the adjacent bags. Further, the piling or formation of packages of the bags in the manner indicated, has 60 necessitated a loss of time on the part of the chief operator, or has required the employment of special help for this service. These objections are overcome by the present invention, where the chief operator is enabled to 65 sever the connecting thread 12 and place the severed bags in suitable packages, arranged with reference to the opening thereon in the manner desired and this without loss of time or distraction of attention from the 70 main work in hand. To this end, a disk cutting blade 13 is rigidly mounted on a bolt shaft 14, bearings for which are provided in a short standard. Rigidly mounted on the said shaft, is a beveled friction wheel 16, by 75 which rotary motion is transmitted to the shaft 14. The standard 15 is rigidly mounted on the table 17 of a sewing machine of the character illustrated in the accompanying drawings. Movement is imparted to the 80 shaft 14 by a transmission shaft 18. The shaft 18 is mounted in bearings 19, set out from a plate 20. The plate 20 has a perforation 21 to receive a lag bolt 22, by which the said plate 20 is secured to the machine 85 head. The shaft 18 is connected to drive the wheel 16 and blade 13 connected therewith, by means of a friction disk 23. The face of the disk 23 is adapted to bear against the periphery of the wheel 16 to drive the 90 same. The proportionate rate of speed imparted by the disk 23 to the wheel 16 and shaft 14, is governed by the "set" of the standard 15, and parts mounted thereon, with reference to the said disk. The speed 95 of the shaft 18 is determined by the ratio of the driven pulley 24 and the driving wheel 25, with which the sewing machine head is equipped. The frictional engagement between the wheel 16 and the disk 100 23, is governed by the expansion spring 26, which normally rests upon the boss for one of the bearings 19 and thrusts against an adjustable collar 27, fixedly mounted on the shaft 18, by means of a set screw 28. The 105 blade 13 is protected by a housing 29. The housing 29 is partly cut away to provide a free-way 30, by which the thread 12 may be inserted under the blade 13 and against the cutting edge thereof, to be severed thereby. The housing 29 is closed by a removable cover, 31, shown best in Fig. 5 of the 110

drawings. The cover 31 has a central opening 32, to give access to the nut 33, which tightens the blade 13 on the shaft 14. By means of the opening 32, the nut may be set up without removing said cover. To correspond with the free-way 30 in the housing 29, the cover 31 has a recess 34, arranged also to provide for the passage of the thread 12 under the said cover.

10 *Operation.*—When a sewing machine head is provided with an attachment of the character described, the operation usually followed in sewing articles such as the bags 11, is as follows: The initial bag or first bag of 15 the series is sewed in the manner indicated, the sewing being started at the end of the bag, which is subsequently to be the mouth of the bag. The sewing follows the long edge of the bag or side seam thereof. Having arrived at the bottom edge of the bag, 20 the line of sewing passes across to close the said bottom edge and arrives at the end of the bottom edge adjacent the side of the bag which is formed by the folded material. 25 The sewing of the particular bag is then completed. The operator before beginning to sew the second or following bag, draws the thread 12 from the supply, with which 30 the sewing machine is furnished. The needle is then inserted in the second or following article adjacent the opening edge thereof to begin sewing the long edge of the bag. This seam having been started, the operator is free to move the previous article 35 and the thread 12 connecting the seam with the article now being sewed, toward the

blade 13, passing the connecting portion of the thread 12, into the free-way 30 and under the cutting edge of the blade 13. The blade 13 immediately severs the connecting 40 thread, freeing the article from the bag being sewed, so that the operator may without lost motion or distraction of attention, place the article thus freed on the package or pile of bags being sewed. This operation is continued for each successive article, thereby avoiding the formation of the chain above referred to, illustrated in Fig. 6 of the drawings.

Claim:

An attachment for a sewing machine comprising a cutting blade disposed adjacent the needle bar of a sewing machine, said blade being disposed in angular relation to the line of feed of said machine; a transmission mechanism operatively connecting said blade and the driving mechanism of a sewing machine; a housing for said blade to protect the major portion of the cutting edge thereof, said housing being lifted to 55 admit the passing of a thread thereunder to be cut by said blade; and a removable cover for said housing arranged to expose said blade.

In witness whereof I have signed my 60 name to this specification in the presence of two subscribing witnesses.

CHARLES WINTHROP CARMAN.
